FOOT SUPPORT.

Application filed May 29, 1926, Serial No. 112,549, and in Great Britain April 1, 1926.

This invention relates to foot supports such as are commonly used for supporting the arches of the foot.

Such supports, as usually constructed consist of a metal spring plate of the desired shape and resiliency sometimes attached to the underside of a leather covering upon which the foot rests.

The resiliency of the under metal plate or spring necessitates that the forward edge of the plate continually move backwards and forwards upon the inner surface of the sole of the boot or shoe and it has been found that the edge of this plate, although it is usually bevelled, cuts into the shoe.

In order to obviate this it has been suggested to encase the forward end of the plate in a leather casing but this is not a completely satisfactory solution of the problem.

According to my invention I provide upon the underside of the resilient metal supporting plate or spring a secondary thin metal or other bearing plate.

This thin metal bearing plate may be attached in any convenient manner to the supporting plate so long as the arrangement is such as to permit of the supporting plate moving relatively upon the bearing plate.

In the accompanying drawings I have illustrated by way of example, certain arrangements which prove satisfactory in practice Figure 1 being a plan of one form of device, Figure 2 a plan of a slight modification and Figure 3 a side elevation of the said modification.

Referring to these drawings the numeral 1 designates the more or less usual metal arch support and is mounted upon a leather base in the usual manner.

40 The numeral 2 designates a bearing plate which may consist of a thin stamping of rustless metal or it may be celluloid or the like upon the forward end 3 of which the forward end of the arch supporting plate

45 1 bears, the rear end 4 of the bearing plate being connected to the forward portion of the crown of the supporting plate by rivets or the like. The said forward end may be integral with the rear end as in Figures 2 and 3 or it may be made separately and connected thereto either through the medium of a tongue

and slot connection as shown in Figure 1 or may be riveted thereto or otherwise suitably attached.

Many other methods of connection may however be adopted so long as the arrangement is such that when the weight of the foot comes upon the arch support 1 the thin bearing plate is so held to the inner surface of the shoe sole as to form a bearing plate upon which the forward end of the arch supporting plate 1 rides.

What I claim and desire to secure by Letters Patent is:—

1. A foot arch support comprising a metal arch, a non-metallic covering and a secondary bearing plate, the rear edge of the metal arch being free to rest on the sole of the boot while its front edge only is protected by the front edge of the secondary bearing plate, the secondary bearing plate being shorter than the metal arch and secured at its rear end in the arch, the metal arch being secured to the non-metallic covering.

2. A foot arch support comprising a metal arch, a non-metallic covering and a secondary bearing plate, the front edge of the metal arch being arranged to bear on the front portion of the secondary bearing plate, while the rear portion of the secondary bearing plate extends only to, and is secured in, the crown portion of the metal arch, the metal arch being secured to the non-metallic covering.

3. A foot arch support comprising a metal arch, a non-metallic covering and a T shaped secondary bearing plate, the front edge of the metal arch being arranged to bear on the transverse members of the T shaped plate, while the narrow end of the T shaped plate extends only to, and is secured in, the crown portion of the metal arch, the metal arch being secured to the non-metallic covering.

4. A foot arch support comprising a metal arch, a leather covering, a secondary bearing plate, the secondary bearing plate being more flexible than, and less than half the length of the metal arch and curved away from the metal arch, its rearward end being riveted to the forward portion of the crown of the arch of the metal arch while its forward edge extends freely beyond the forward edge of the metal arch.

5. A foot arch support comprising a plate metal arch, a leather covering, and a T shaped secondary bearing plate, the secondary bearing plate being more flexible than the plate metal arch and its forward transverse portion arranged to support the front edge of the plate metal arch while the rear narrow por-

tion of the T is curved away from the plate metal arch and its rear end riveted to the forward portion of the crown of the arch, 10 the plate metal arch being secured to the leather covering.

In witness whereof I affix my signature.
PERCIVAL GEORGE HAMLYN HINDER.
